UNITED STATES PATENT OFFICE

ANTHONY P. GEIMER, OF TWO RIVERS, WISCONSIN, ASSIGNOR TO HAMILTON MANUFACTURING CO., OF TWO RIVERS, WISCONSIN, A CORPORATION OF WISCONSIN

CABINET

Application filed December 3, 1927. Serial No. 237,486.

My invention relates to cabinets having drawers and resides in the provision of an improved construction of runways or the provision of an improved construction of elements in conjunction with runways whereby the drawers are held from vertical displacement from the runways within the normal travel of the drawers.

My invention is of particular use in connection with cabinets having runways adapted to support printers' galleys, the galleys being considered as one form of drawer with which the cabinet is supplied.

In accordance with my invention, metallic strips are placed substantially parallel to and above the runways, these strips being pressed laterally and inwardly into inwardly projecting formations which overhang the runways and lateral portions of the drawers which enter between the runways and said inwardly projecting formations. In the preferred embodiment of the invention, the runways are also of strip material and are integrally formed with the aforesaid strip members, each runway and the corresponding strip above it being preferably a length of angle iron. Said strip members and the formations at the tops thereof which overlie the runways proper constitute guards that confine the drawers to their lines of travel and prevent them from tilting. In the case of galleys, the printing faces of the type or forms held by the galleys are thus protected from injurious contact with the galleys above.

The upper portions of these guards desirably terminate short of the runways and preferably also of the outer sides of the guards at each drawer receiving face of the cabinet to permit the entering end of the drawer to be readily rested upon the receiving ends of the runways.

The invention will be more fully explained in connection with the accompanying drawing in which Fig. 1 is a front view of the cabinet as it may be constructed in accordance with my invention; Fig. 2 is a sectional view on line 2—2 of Fig. 1; Fig. 3 is a sectional view on line 3—3 of Fig. 2; Fig. 4 is a sectional view, on a larger scale, on line 4—4 of Fig. 2; Fig. 5 is a perspective view illustrat-

ing a portion of one runway and its associate guard together with the contiguous side of the cabinet, a portion of the rear end of the drawer being shown in place upon the runway; and Fig. 6 is a view similar to a part of Fig. 3 with the entering end of a drawer resting upon the receiving ends of the runways preparatory to the full insertion of the drawer.

The cabinet 1 illustrated may, if desired, be formed of wood. The drawers 2 that are illustrated within the cabinet are in the nature of galleys, though the invention is not to be thus restricted. Each galley shown has a floor 3 of sheet metal which is folded upon itself lengthwise of the galley to constitute lateral projections 4. The metal of which the parts 3 and 4 are made is then continued upwardly to form the galley sides 5, the metal being finally downwardly continued as indicated at 6 to strengthen the structure. The metal is preferably folded at its rear end to form the back wall 7, the sides 5 being folded inwardly as indicated at 8. The parts 7 and 8 may be spot welded, if desired. The runways 9 are desirably made of strip metal. These runways are preferably provided with integral continuations 10 which are also in the form of strip metal portions and are shaped to constitute guards to hold the drawers in their lines of travel.

The two formations 9 and 10 are preferably made of angle iron, the runways 9 being horizontal and the strips 10 rising from the runways at the outer longitudinal edges 85 of the runways where the parts 9 and 10 are in integral connection. The upper portions of the strip members 10 are depressed and pressed laterally and inwardly into elongated upright U-shaped inwardly projecting 90 guard formations whose base portions 11 extend lengthwise of the runways 9 and are substantially parallel therewith, the side portions 12 of the U-shaped formations terminating short of the runways and of the upright and outer side portions of the guards. Each runway, the upright side of the contiguous guard, and the elongate top portion 11 of such guard, are collectively of U-shape 95 in cross section and constitute a channel way 100.

that receives the contiguous lateral projection 4 of the drawer, the narrower side 11 of such channel way overlying such projection and the broader side 9 of such channel way 5 extending inwardly beyond the channel side 11 and inwardly beyond the contiguous drawer projection 4 whereby the drawer has broad support and is properly confined to its line of travel during the major portions 10 of its movements. If the drawers happen to be galleys, the printing faces of the galley contents are prevented from being injured by the galleys or cabinet portions above.

By terminating the U-shaped formations 15 11, 12 short of the runways, the entering ends of the drawers may be freely lowered upon the receiving ends of the runways without interference from the guards and to positions in which the drawers may be readily slid into 20 place. By also terminating the overhanging portions 11, 12 of the guards short of the upright sides of the guards, ample room is afforded for the fastening screws or means 13 which are disposed at the outer ends of 25 the side portions of the guards.

Having thus described my invention, I claim:

1. A cabinet having a removable drawer provided with a lateral continuation on each 30 side, two runways mounted one on each side wall of the cabinet and on which the lateral continuations of the drawer respectively ride, a guard element carried by the cabinet along each runway, each of said elements 35 having an upper portion overlying and vertically spaced from its related runway which latter projects laterally and inwardly beyond the overlying portion of its related guard element, and said upper overlying portion 40 terminating short of the ends of its related guard element and runway which are located at the drawer receiving face of the cabinet to permit the entering end of the drawer to be readily rested on the drawer receiving 45 ends of the runways.

2. A cabinet having a removable drawer provided with a lateral continuation on each side, two runways mounted one on each side wall of the cabinet and on which the lateral 50 continuations of the drawer respectively ride, a guard element carried by the cabinet along each runway, each of said elements having an upper portion overlying and vertically spaced from its related runway and 55 which terminates short of the ends of its related guard element and runway which are located at the drawer receiving face of the cabinet to permit the entering end of the drawer to be readily rested on the drawer receiving 60 ends of the runways.

3. A cabinet having a removable drawer, two runways mounted one on each side wall of the cabinet and by which the drawer is slidably supported, a guard element carried 65 by the cabinet along each runway, each of

said elements having an upper portion overlying and vertically spaced from its related runway and which terminates short of the ends of its related guard element and runway which are located at the drawer receiving face of the cabinet to permit the entering end of the drawer to be readily rested on the drawer receiving ends of the runways.

In witness whereof, I hereunto subscribe my name.

ANTHONY P. GEIMER.
